FOLDING STEP LADDER

Joseph V. Rossi, Chicago, Ill., assignor to Comfort
Lines, Inc., Chicago, Ill.

Filed May 6, 1971, Ser. No. 141,092

Term of patent 14 years

Int. Cl. D6—02

U.S. Cl. D6—35

Fig. 1

Fig. 2

FIG. 1 is a perspective view of the folding step ladder showing my new design;

FIG. 2 is a perspective view of the folding step ladder in its folded condition;

FIG. 3 is a side elevational view of the folding step ladder as seen in FIG. 1;

FIG. 4 is a top plan view of the folding step ladder as seen in FIG. 1;

FIG. 5 is a front elevational view of the folding step ladder as seen in FIG. 1; and

FIG. 6 is a rear elevational view of the folding step ladder as seen in FIG. 1.

I claim:

The ornamental design for a folding step ladder, substantially as shown.
